US0D1107762S

(12) **United States Design Patent** (10) **Patent No.:** **US D1,107,762 S**
(45) **Date of Patent:** **** Dec. 30, 2025**

(54) **TIP FOR A GROUND ENGAGING MACHINE IMPLEMENT**

(71) Applicant: **Caterpillar Inc.**, Peoria, IL (US)

(72) Inventor: **Corey M. Wells**, East Peoria, IL (US)

(73) Assignee: **Caterpillar Inc.**, Peoria, IL (US)

(**) Term: **15 Years**

(21) Appl. No.: **29/951,159**

(22) Filed: **Jul. 8, 2024**

(51) **LOC (15) Cl.** **15-03**

(52) **U.S. Cl.**

USPC **D15/29**; D15/28

(57) **CLAIM**

The ornamental design for a tip for a ground engaging machine implement as shown and described.

DESCRIPTION

FIG. 1 is a perspective view of a tip for a ground engaging machine implement showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
